UNITED STATES PATENT OFFICE.

SAMUEL K. DENNIS, OF CHICAGO, ILLINOIS, ASSIGNOR, BY MESNE ASSIGNMENTS, TO INTERNATIONAL HARVESTER COMPANY, A CORPORATION OF NEW JERSEY.

CULTIVATOR.

1,408,990.

Specification of Letters Patent.

Patented Mar. 7, 1922.

Application filed September 3, 1914. Serial No. 860,035.

To all whom it may concern:

Be it known that I, SAMUEL K. DENNIS, a citizen of the United States, residing at Chicago, in the county of Cook and State of Illinois, have invented certain new and useful Improvements in Cultivators, of which the following is a full, clear, and exact specification.

This invention relates to cultivators, and has for its object to simplify and improve the construction and operation thereof in a manner to enlarge the scope of their employment.

As is well known there exists to-day a manifold variety of cultivators, which are made necessary on account of slight differences in the conditions under which they are operated, and the disadvantage of this is felt strongly by the manufacturers who must perform supply a machine for each and every demand. With this in view I have provided a cultivator of great adaptability embodying a simple combination of the essential parts, and employing a coherent arrangement of adjustments to thereby suit the cultivator to a maximum latitude of uses so that one type will serve the purposes which could heretofore be met only by a variety of cultivators.

Entering into this combination are: improved connections between each of the gang members and its carrying member including the employment of means whereby the beams may be held in parallel relation and independently adjusted laterally, which means will supplant and perform all of the functions of the adjustable jockey arches now in use, and in addition will afford convenient means for holding either or both gang members away from the center of the machine, as is desirable in cultivating on the side of a hill.

One form which my invention may assume is exemplified in the following description and illustrated in the accompanying drawings, in which—

Figure 1 shows a vertical longitudinal sectional view of a cultivator embodying my invention:

Figure 2 shows a detailed view in plan of the means for mounting each of the beams upon its supporting member;

Figure 3 shows a detailed view in elevation of the parts shown in Figure 2; and,

Figure 4 shows the adjustable connection 55 employed for holding the beam against lateral movement.

Referring in detail to the form of my invention illustrated herewith it will be seen that I have provided a cultivator having 60 carrying wheels 10, an arched axle 11, a draft tongue 12 connected with the arched axle, a front yoke member 13 carried on the tongue rigidly therewith, cultivator beams 14 connected to the front yoke member and 65 provided with hand bars 14^a projecting upwardly, and a driver's seat 12^a pivoted to the tongue and adapted to be folded therover when it is desired to convert the machine into a walking cultivator. 70

The connections between the gang members and the yoke members are as follows: The ends of the yoke member 13 are provided with horizontal extensions or spindle portions 15 upon each of which is rotatably 75 mounted a sleeve 16, said sleeve being provided in its front wall with a longitudinal slot. Into this slot is inserted a bolt 18, the surrounding wall of the sleeve being sufficiently spaced from the spindle portion 15 80 to permit the bolt head to reside between the parts. A clamping member 20 is arranged upon the bolt in non-rotatable engagement with the sleeve, and its periphery is beveled or cone-shaped, to enter a coacting clamping 85 member 22, which latter is provided with a curved portion within which is seated a member 24 having the forked ends 25 of one of the cultivator beams pivoted thereto for horizontal movement. This member is provided with a vertical slot through which the bolt 18 is extended and clamped thereto by means of a nut and washer 27. 90

With this construction when the nut 27 is loosened the cultivator beam may be moved 95 in a vertical direction and in a lateral direction, and may be rotated in either direction on a longitudinal axis on account of the clamping members 20 and 22. This coupling forms the subject matter of my divisional application Serial Number 467,378, filed May 6, 1921. 100

The forked members 25, as will be seen, are in two parts, each detachably connected

with a beam 14 by means of two bolts 28, one of the bolts being received in slots 29 so that the two parts may be swung away from each other for the purpose of allowing the member 24 to be inserted. The pivotal connection between the forked member and the member 24 is accomplished by providing depressions 30 in the ends of the forked member, into which depressions the member 26 is 10 rotatably fitted, and a bolt 31, vertically positioned, connects the coacting parts in pivotal relation. Each of the cultivator beams is thus free to be swung laterally, with the bolts 31 as its axis.

15 Upon the outer end of the rotatable sleeve 16 there is formed a crank arm 32 normally projected downward and at its lower end provided with openings 33, into any one of which is fitted a rod 34, and at the other end 20 of the rod a contractible coil spring 35 is arranged, which spring is connected to a bracket member 36 fastened upon the horizontal portion of the arched axle, said connection being through a short link 37 screw 25 threaded and provided with a hand nut 38 for adjusting the tension of the spring. This spring, it will be understood, is for the purpose of assisting in the vertical movement of the gang member. A brace bar 39 is 30 diagonally arranged between the outer end of the spindle portion 15 and the horizontal portion of the arched axle, being also fastened to the bracket 36, which bracket is so mounted that it permits a rotatable movement 35 of the arched axle. Obviously, this brace bar serves to rigidly support the yoke member 13 and to otherwise reinforce the cultivator frame.

30 The lifting spring, it will be seen, occupies a position directly behind the brace bar 39, and for this reason a more simple appearance is given the cultivator frame and the spring is protected against injury due to striking obstructions, as it often does where arranged 45 forwardly of the cultivator and connected to the tongue. The important advantage of such an arrangement, however, is that all strains are removed from the tongue or other portions of the forward frame and the strain 50 is thrown longitudinally upon the bar 39 which, obviously, would have no damaging effect. Another great advantage of this arrangement of the spring is that it enables me to locate this part on the outer end of the spindle portion 15 and thereby, in an operative cultivator, the springs are further separated from the row of corn and the downwardly extending crank arms 32 will not 55 strike the young plants and injure them.

60 My improved arrangement of the lifting springs is particularly advantageous when used in connection with two-row cultivators, for then the immense strains now thrown upon the tongue, and which after short use 65 causes that member to visibly sag and

weaken, would be entirely removed and the strains, if any, absorbed by the diagonal brace bars. Moreover, by having the springs arranged as shown, the thumb nuts for adjusting their tension may be located near the 70 driver's seat, which enables the operator to quickly and conveniently manipulate them without leaving his seat.

Loosely connected to the lower end of each of the diagonal brace bars is a link 39^a extending in a substantially horizontal direction through an opening in the bent end of a bar 40 and along the flat surface of the bar for a short distance, where a bent end or projection 39^b is inserted in one of a series 80 of openings 41 formed in said bar. The bent end of the link is held in position in this opening by a cotter pin 42, or otherwise. The bar 40 is pivoted to the lower end of the upright portion of the arched axle adjacent 85 to the spindle portion thereof, preferably by a projection 43 circular in cross section which has a bent end 43^a extended through the bar and held therein also by a cotter pin.

90 This extensible bar serves to assist the diagonal bar in reinforcing the parts of the cultivator, and it is readily adjustable to permit the carrying wheels to be moved forwardly or rearwardly, as may be desired, to provide a proper balance for the weight of 95 the driver. The adjustment is made simply by removing the cotter pin 42 from the lug 39^b swinging the link 39^a outwardly from the bar 40, and then adjusting the two members longitudinally, drawing them together 100 or pulling them apart as may be desired until the proper length has been reached. An extensible bar of this character has the important advantage that no tools are necessary in making an adjustment. Moreover, it 105 is particularly adapted for a cultivator of the present construction inasmuch as it in no wise interferes with the operation of the other parts, and its adjustable connection is easily accessible to the operator at all times.

110 The means for adjustably holding each of the beams against lateral movement is best shown in Figures 2, 3 and 4 and comprises a bracket formed of a pair of spaced arms 44 pivotally connected to the spindle portion 15, and extending rearwardly for a short distance where a notched or rack bar 45 connects the two ends. The notches on the bar 45 are formed by a series of studs 46 spaced apart, as shown in Figure 4, and as now constructed the two arms 44 are 115 preferably reinforced intermediately by an integral cross brace 47. A small contractible coil spring 48 is connected with the large lifting spring 35, and has a connection with one of the arms 44 for keeping the notched bar 45 in engagement with the bifurcated end 49 of a collar 50 carried adjustably on the beam. Upon the diagonal brace bar 39 is carried, by means of an ad- 120

justable collar 51, a stop lug 52 which engages with one of the arms 44 and limits the upward movement thereof.

The operation of the adjustable locking device just described is as follows: Normally, with the beams in working position, the forked lugs 49 will engage with the studs 46 and lock the beam against lateral movement. Any slight vertical shift in the beam will obviously be followed by a similar movement on the part of the bracket 44 on account of the spring 48, and no unlocking of the parts can therefore occur in the usual operation of the device. However, when the end of the row of plants is reached and it is desired to turn around, or transport the cultivator for any considerable distance, the operator will raise the ground tilling members entirely out of the ground through an upward movement of the hand bars 14^a, assisted by the lifting springs 35. The stop lug 52 will then intervene and limit the upward movement of the arms 44 so that the lugs 49 on the beam can be disengaged from the notched bar 45, and thereupon the beams will be free to swing laterally, and the operator may rest them upon the hooks 53 carried upon the lower ends of the arched axle for that purpose. This is an advantage, inasmuch as the cultivator need not, necessarily, be provided with lifting levers, whereas, heretofore, such separate levers have always been essential when a spreader arch is used. The arch, it will be understood, would prevent the beams from being readily moved apart to position on the rest hooks 53.

It is obvious that either one of the beams may be moved to any desired position in a lateral direction, and locked in that position when lowered on account of the engagement between the lugs 49 and the rack bar 45. Both beams are thus given an independent adjustment, and at the same time may be held in parallel relation. On account of the method of mounting the arms 44 and associated parts it is obvious that the device just described can be made to conform to the varying adjustments of which each of the beams is capable. Moreover, the form of cultivator shown herewith is particularly adapted to receive such a locking device inasmuch as the lifting spring 35 can be made use of to assist in the movement of the arms 44, the diagonal brace bar 39 being also specially convenient for the reception of the stop member 51. This device can be used to perform all the functions of the adjustable jockey arches now in use, and in addition offers a new result in that both beams may be swung to one side of the cultivator and locked in that position, which is desirable in cultivating corn on a side hill.

While I have shown and described but

one embodiment of my invention herein it is to be understood that it is susceptible of modification, and therefore changes in the construction and arrangement of the several parts may be resorted to without departing from the spirit of the invention as disclosed in the appended claims.

What I claim and desire to secure by Letters Patent is:

1. In a cultivator, a plurality of laterally and vertically movable beams, means for permitting lateral adjustment of said beams at a given point in the vertical movement, and adjustable means for predetermining the point in the vertical movement of said beams at which they are released for lateral movement.

2. In a cultivator, a plurality of laterally movable beams pivotally mounted for up and down movement, and means carried by the frame for holding said beams against lateral movement when in working position and automatically released therefrom when said beams are raised to a predetermined point.

3. In a cultivator, a plurality of laterally movable beams pivotally mounted for up and down movement, and means movable up and down with said beams and capable of holding them against lateral movement and automatically released therefrom when said beams are raised to their extreme limit of upward movement.

4. In a cultivator, a frame, laterally movable beams pivotally mounted thereon, an arm for each of said beams carried on the pivotal mounting, a spring for moving said arm in conformity with the beams, and means on said arm for locking the beam against lateral movement when in working position.

5. In a cultivator, a frame, a laterally movable beam pivotally mounted thereon, an arm carried on said frame and extending rearwardly, and provided with means for locking said beam against lateral movement, means for raising said arm in conformity with the beam, and a stop device for limiting the upward movement of said arm.

6. In a cultivator, a front yoke member, beams pivotally mounted thereon, brace bars extending diagonally from said yoke member, lifting springs for assisting in the vertical movement of said beams, means carried by said yoke member for adjustably locking each of said beams against lateral movement, a connection between said locking means and adjacent lifting spring for moving it in conformity with the beam, and an adjustable stop device carried by each of said diagonal brace bars for limiting the upward movement of said locking means.

7. In a cultivator, an axle, a frame, a yoke member thereon, gang members carried by the yoke member, a diagonally arranged

brace bar between the yoke member and axle, and a substantially horizontal extensible bar connected at one end to the lower end of the diagonal bar and at its other end to the lower end of the upright portion of the arched axle, said extensible bar comprising a link member and a flat bar said flat bar being provided at one end with a bearing to receive the link member, said link member 10 being provided with a projection to engage

one of a series of openings in said bar, and means for retaining said projection in position within the opening.

In testimony whereof I affix my signature, in the presence of two witnesses.

SAMUEL K. DENNIS.
